(57) **CLAIM**

The ornamental design for a unitary table support, as shown and described.

DESCRIPTION

FIG. 1 is a front, top perspective view of a unitary table support showing my new design;

FIG. 2 is a front, bottom perspective view of the unitary table support;

FIG. 3 is a right side view of the unitary table support, a left side view being a mirror image thereof;

FIG. 4 is a front view of the unitary table support;

FIG. 5 is a top view of the unitary table support, with the environment removed; and,

FIG. 6 is a bottom view of the unitary table support, with the environment removed.

The broken line showing in FIGS. 1, 2, and 3 is for the purpose of illustrating environment and forms no part of the claimed design.
